US00D901737S

(12) **United States Design Patent** (10) Patent No.: **US D901,737 S**
(45) Date of Patent: **** Nov. 10, 2020**

(54)	WEARABLE HEADGEAR DEVICE	1,688,113 A	10/1928	Bornkessel
(71)	Applicant: Integra LifeSciences Corporation , Plainsboro, NJ (US)	2,217,359 A	10/1940	Cooke
(72)	Inventors: Brian Neeley , Cottage Grove, WI (US); Greg Falendysz , Sun Prairie, WI (US); Steve Dieter , Oregon, WI (US); Parker Hren , Madison, WI (US); Nick Higbee , Madison, WI (US); Frank Thomas Poggio , Hoffman Estates, IL (US); Jaime Luis Prats , York, PA (US); Thomas Joseph Africa , Lebanon, OH (US); Lauren Angell , Pataskala, OH (US); Kenny Snyder , Lancaster, PA (US); Eric Gillman , Ringwood, NJ (US)	2,437,748 A	3/1948	Malcom
(73)	Assignee: Integra LifeSciences Corporation , Princeton, NJ (US)	2,883,980 A	4/1959	Storz, Jr.
(**)	Term: 15 Years	2,893,379 A	7/1959	Springer
(21)	Appl. No.: 29/665,581	3,008,040 A	11/1961	Moore
(22)	Filed: Oct. 4, 2018	3,047,876 A	8/1962	Malcom
(51)	LOC (12) Cl. 26-02	3,285,242 A	11/1966	Wallace
(52)	U.S. Cl. USPC D26/39	3,470,570 A	10/1969	Christiansen

CLAIM

The ornamental design for a wearable headgear device, as shown and described.

DESCRIPTION

FIG. 1 is a top perspective view of a wearable headgear device according to the present invention;

FIG. 2 is a rear view of the wearable headgear device of FIG. 1;

FIG. 3 is a front view of the wearable headgear device of FIG. 1;

FIG. 4 is a top view of the wearable headgear device of FIG. 1;

FIG. 5 is a bottom view of the wearable headgear device of FIG. 1;

FIG. 6 is a left side view of the wearable headgear device of FIG. 1;

FIG. 7 is a right side view of the wearable headgear device of FIG. 1;

FIG. 8 is a top perspective view of a wearable headgear device according to another embodiment of the present invention;

FIG. 9 is a rear view of the wearable headgear device of FIG. 8;

FIG. 10 is a front view of the wearable headgear device of FIG. 8;

FIG. 11 is a top view of the wearable headgear device of FIG. 8;

FIG. 12 is a bottom view of the wearable headgear device of FIG. 8;

FIG. 13 is a left side view of the wearable headgear device of FIG. 8; and,

FIG. 14 is a right side view of the wearable headgear device of FIG. 8.

The broken lines show portions of the article which form no part of the claimed design.
